UNITED STATES PATENT OFFICE.

EDWARD B. GALLAHER, OF NORWALK, CONNECTICUT, ASSIGNOR TO CLOVER MANUFACTURING CO., A CORPORATION OF NEW YORK.

DESIGN FOR A BOX.

52,387.

Specification for Design. Patented Sept. 10, 1918.

Application filed October 28, 1915. Serial No. 58,507. Term of patent 14 years.

To all whom it may concern:

Be it known that I, EDWARD B. GALLAHER, a citizen of the United States, residing at Norwalk, in the county of Fairfield and State of Connecticut, have invented a new, original, and ornamental Design for Boxes, of which the following is a specification, reference being had to the accompanying drawing, forming part thereof.

Fig. 2 is a plan view thereof;

Fig. 3 is a perspective view thereof.

I claim:

The ornamental design for a box, as shown.

EDWARD B. GALLAHER.
